his Attorney.

UNITED STATES PATENT OFFICE.

JAMES H. MATTHEWS, OF PITTSBURGH, PENNSYLVANIA, ASSIGNOR TO JAS. H. MATTHEWS & CO., OF PITTSBURGH, PENNSYLVANIA, A CORPORATION OF PENNSYLVANIA.

DIE.

1,078,601.

Specification of Letters Patent.

Patented Nov. 11, 1913.

Application filed May 12, 1913. Serial No. 766,932.

To all whom it may concern:

Be it known that I, JAMES H. MATTHEWS, a citizen of the United States, and residing in the city of Pittsburgh, in the county of Allegheny and State of Pennsylvania, have invented or discovered new and useful Improvements in Dies, of which the following is a specification.

My invention relates to steel stamping or 10 impression dies.

More particularly it comprises new and improved means for mounting and securing interchangeable type blocks in said dies.

The objects in view are the provision of 15 means for that purpose which will permit the ready installation or removal of said type blocks and which will securely hold them in place against accidental loosening or dismounting.

20 A further object is to insure the proper setting of the type, thus preventing the loss of time and injury to the type which results from improper setting of the same in the die.

25 These objects are accomplished by providing the type slot or recess with a locking-bar having a cam portion which, when the bar is turned to one position engages grooves in the type-blocks and locks the 30 latter rigidly in place, but, when said bar is turned to the opposite position, releases said blocks and permits their ready removal or installation in the slot. Means are provided for locking the said bar in 35 either position. No loose or detachable parts are used which might become lost and cause great inconvenience and no hammer or other tool is required to operate said locking bar.

40 In the accompanying drawings, I have illustrated my invention, for the sake of clearness in connection with a hammer-die but it will be understood that it may as readily be applied to any form of hand or 45 machine operated die.

In said drawings, Figure 1 is a perspective of a hammer-die fitted with my invention; Fig. 2 is a horizontal sectional view of the die shown in Fig. 1, showing the bar 50 in its unlocked position; Fig. 3 is a similar view showing the bar in its locking posi-

tion; Fig. 4 is an enlarged perspective of the locking-bar dismounted, and Fig. 5 is a perspective of one of the type blocks.

The following is a detailed description of 55 the drawings:

A is the die, such for instance the hammer-die shown; and 1 is the slot or recess in which the interchangeable type-blocks B are set.

2 is a bore, preferably cylindrical running transversely through the die A and intersecting the side wall of the slot 1, said bore forming a semi-circular recess in said side wall along the line of intersection.

60 C is the locking-bar seated in said bore 2 and capable of both longitudinal and rotary movement therein. The portion of said locking-bar which intersects the slot 1 is cut away so as to form a semi-circular cam 65

3 which, when said bar is turned into the position shown in Fig. 2 occupies the bore 2, but, when said bar is turned 180° into the position shown in Fig. 3, extends into the slot 1. The type-blocks B are provided 70 with semi-circular grooves 4 in their edges which are adapted to engage said cam 3, when said locking-bar is properly turned, thus locking said blocks securely in said slot 1. By turning the bar into the opposite position, said blocks are released and 75 may be removed from said slot 1 or blocks may be freely inserted into said slot. As shown in the drawings, said locking-bar and bore are below the horizontal center of the 80 slot 1 and the grooves 4 are below the center of the blocks B so that said blocks must be set in the proper position to be locked in said slot, the grooves 4 being provided on 85 only one face of said blocks. By this arrangement improper setting or reversal of the blocks in the slot is impossible, thus avoiding the loss of time and injury to the 90 type which now frequently result from careless and improper setting.

95 One of the protruding ends of bar C is provided with a head 5 between which and the die a spiral spring 6 is coiled about the bar C, thus tending to force the bar toward the right in the drawings. The other protruding end of bar C is bent sharply at right angles, as at 7.

8 is a groove in the end of die A intersecting the bore 2 vertically and forming locking seats for the end 7 of the bar C.

When the bar C assumes the position shown in Fig. 3, locking the blocks B, the end 7 of said bar is held seated in the end of the seat 8 toward the striking face of the die and said bar cannot be released except by pressing inwardly on the head 5, compressing the spring 6, and lifting the end 7 out of said seat 8. The bar may then be rotated to assume its releasing position, as shown in Fig. 2, whereupon, the pressure on head 5 being released, the end 7 seats in the opposite end of seat 8. The bar may be reversed into its locking position by again pressing on the head 5 to lift the end 7 from its seat 8 and turning the bar so that its cam is advanced into the slot 1 in engagement with the grooves 4 of the type-blocks B. Removal of pressure from the head 5 will permit the end 7 of the bar to spring into and lock itself in the portion of the seat 8 adjacent to the striking face of the die A, 25 the position first above described.

It is evident that the type-blocks may be readily installed in or removed from the slot 1, locked or unlocked therein, and that their proper setting in said slot is insured. No loose or unattached parts are used which may become lost and cause inconvenience and the mechanism is simple, inexpensive and contains no element likely to wear out or be broken. The use of the die in striking the necessary blows will not loosen the locking bar but the type-blocks are held securely in place, which is impossible where wedge members or set-screws are used to hold the type-blocks in the slot.

40 What I desire to claim is:—

1. The combination of a die provided with a type-slot, type adapted to be set in said slot and provided with locking grooves, a bar mounted to rock in said die and provided with a cam adapted to engage said

locking grooves and hold said type in said slot, and resilient means whereby said bar is automatically locked in its position wherein said cam engages said grooves.

2. The combination of a die provided with a type-slot in the face thereof and a locking seat in one end, type adapted to be set in said slot and provided with grooves, a rocking bar mounted in said die and having a cam portion adapted to engage said grooves to secure said type in place when said bar is rocked into proper position, and resilient means for holding the end of said bar in said seat and preventing its accidental rotation when said bar is in its locking position.

3. The combination of a die provided with a type-slot in the face thereof and a locking seat in one end, type adapted to be set in said slot and provided with grooves, a rocking bar mounted in said die and having an angular protruding end, said bar being provided with a cam portion adapted to engage said grooves and lock said type in said type-slot, when said bar is rocked into proper position, and resilient means for holding the angular end of said bar in said locking seat when said bar is in its locking position.

4. The combination of a die provided with a type-slot, type adapted to be set in said slot and provided with locking grooves, a bar mounted in said die and capable of rocking and longitudinal movements, said bar being provided with a cam which, when said bar is rocked into its proper position, engages said grooves and locks said type in said slot, and resilient means for holding said bar stationary when in its type-locking position.

Signed at Pittsburgh, Penna., this 10th day of May, 1913.

JAMES H. MATTHEWS.
